UNITED STATES PATENT OFFICE.

HENDRICKS S. MUNDY, OF GUTHRIE, OKLAHOMA TERRITORY.

DESIGN FOR A BODY FOR ROLLING STREET-STANDS.

SPECIFICATION forming part of Design No. 28,994, dated July 5, 1898.

Application filed January 18, 1898. Serial No. 667,114. Term of patent 7 years.

To all whom it may concern:

Be it known that I, HENDRICKS S. MUNDY, a citizen of the United States, residing at Guthrie, in the county of Logan and Territory of Oklahoma, have invented a new and original Design for the Body of a Rolling Street-Stand, of which the following is a specification.

This invention relates to a new and original design for the body of a rolling street-stand; and it has for its object to provide a design of this character that shall be both useful and ornamental.

The leading feature of the design resides in an upright approximately rectangular body having at its rear side a vertical door-panel extending the full height thereof and a horizontal offset front extension overhanging the lower base portion of the body and provided at its forward end and opposite sides with rectangular windows.

The minor features of the design are the lower elongated box-like base portion of the body, an arched roof extending the full length of the stand, horizontal shelf-pieces projected from opposite sides of the body, Y-shaped handles arranged at the rear end of the body at opposite sides of the door-panel, and short leg projections at the lower rear corners of the body.

In the drawings, Figure 1 is a perspective view of the body of a rolling street-stand embodying the herein-described design. Fig. 2 is a similar view showing a different position of the body.

Referring to the accompanying drawings, 35 the numeral 1 designates an upright rectangular body having a lower elongated box-like base portion 2 and provided at the lower rear corners thereof with short leg projections 3. The body 1 is provided at its rear side with a 40 vertical door-panel 4, extending the full height thereof, and at opposite sides of said door-panel 4 the body 1 has projected rearwardly therefrom a pair of Y-shaped handle-pieces 5.

45 The upright body 1 is provided with a horizontal offset front extension 6, overhanging the lower base portion 2 and provided at its forward end and opposite sides with rectangular windows 7, said front extension 6 and 50 the rear portion of the body being covered at the top by an arched roof 8, extending the full length of the stand and having projected thereabove a ventilating-pipe 9.

At opposite sides of the body 1, below the 55 plane of the front extension 6, are arranged offstanding horizontal shelf-pieces 10.

What is claimed is—

The design for the body of a rolling street-stand herein shown and described. 60

In testimony that I claim the foregoing as my own I have hereto affixed my signature in the presence of two witnesses.

HENDRICKS S. MUNDY.
